(57) **CLAIM**

The ornamental design for a garment, as shown and described.

DESCRIPTION

FIG. 1 is a top plan view of a portion of the garment shown separate for ease of illustration;

FIG. 2 is a right-side elevational view of the portion of the garment shown separate for ease of illustration;

FIG. 3 is a front elevational view of the portion of the garment shown separate for ease of illustration, the rear elevational view being a mirror image thereof;

FIG. 4 is a left-side elevational view of the portion of the garment shown separate for ease of illustration;

FIG. 5 is a bottom view of the portion of the garment shown separate for ease of illustration;

FIG. 6 is a front elevational view of the portion of the garment assembled to configure the left half of an upper torso article of cloth;

FIG. 7 is a front isometric view of the portion of the garment shown separate for ease of illustration, showing the portion of the garment being used by a model;

FIG. 8 is a rear isometric view of the portion of the garment shown separate for ease of illustration, showing the portion of the garment being used by a model;

FIG. 9 is a side isometric view of the portion of the garment shown separate for ease of illustration, showing the portion of the garment being used by a model; and,

FIG. 10 is a perspective view showing the complete garment.

The broken lines represent environmental structure and form no part of the claimed design.

1 Claim, 4 Drawing Sheets
